UNITED STATES PATENT OFFICE

132,374

DESIGN FOR AN AMMUNITION ROUNDS COUNTER

Richard Daalder, East Paterson, N. J., assignor to
Bendix Aviation Corporation, South Bend, Ind.,
a corporation of Delaware

Application July 16, 1941, Serial No. 102,195

Term of patent 14 years

To all whom it may concern:

Be it known that I, Richard Daalder, a citizen of the United States, residing in East Paterson, in the county of Bergen and State of New Jersey, have invented a new, original, and ornamental Design for an Ammunition Rounds Counter, of which the following is a specification, reference to be had to the accompanying drawing, forming part of this application.

In the drawing:

Fig. 1 is a front elevational view of an ammuni-

tion rounds counter, showing my new design; and

Fig. 2 is a side view on a somewhat reduced scale of the device as illustrated in Fig. 1.

The characteristic features of the design reside in the portions shown in full lines in the drawing.

I claim:

The ornamental design for an ammunition rounds counter, as shown and described.

RICHARD DAALDER.
